UNITED STATES PATENT OFFICE.

OTIS AMOS AND CLAUDE A. DEAL, OF INDIANAPOLIS, INDIANA.

INK-VENDING DEVICE.

Application filed November 10, 1925. Serial No. 68,085.

This invention is a device for the vending of ink for fountain pen filling and comprises means for receiving a coin to permit a lever to be operated such that an ink 5 well filled with a predetermined amount of ink is uncovered.

Residing within the invention are several features, all cooperating to insure its successful operation, such as the means for preventing the ink well from receiving ink 10 more than once upon the deposit of a single coin regardless of the continued manipulation of the operating lever; the means permitting the movement of the operating 15 lever but such that the mechanism is not operated when a coin is not deposited; the means for filling the ink well to a fixed level each time the mechanism is operated regardless of the quantity of ink remaining 20 in the well from previous operations; and the locking means for normally retaining the cover over the ink well.

These and such other objects to be found in the invention will best be understood by 25 the following detailed description of one embodiment of the invention, together with reference to the drawing, in which—

Fig. 1 is a perspective view of the ink 30 vendor shown in an operated condition;

Fig. 2, a right side, fragmentary elevation;

Fig. 3, a left side, fragmentary elevation with the ink vessel removed;

Fig. 4, a rear elevation;

Fig. 5, a bottom plan view of the mechanism as carried by the top plate; and

Fig. 6, a section taken on the line 6—6 in Fig. 2.

Like characters of reference indicate like 40 parts throughout the several views.

The operating mechanism is supported and contained within the box-like housing formed by the bottom 10, the right side 11, the rear end 12, the left side 13, the front 45 side 14, and the top side 15, all suitably joined together, with provision made for access being had to the interior for the removal of the money and the replenishing of the ink supply.

The top side 15 is provided with the central slot 16 into which slot is inserted the crosshead 17 such that its top face is approximately flush with the outer side of the top 15 and the body of the crosshead 17 is 50 depended. A closure plate 18 is rigidly affixed to the top side of the crosshead 17

such that as the crosshead reciprocates in the slot 16, the closure plate 18 reciprocates likewise. This plate 18 projects sufficiently beyond the crosshead 17, on both ends, that 60 the slot 16 is always covered regardless of the position of the crosshead 17 in the slot 16, and the forward end of the plate 18 is so fixed in length that when the crosshead 17 is in its normal inoperative position, as 65 indicated in Figs. 2 and 5, the plate 18 covers the ink well 19.

To retain the crosshead 17 within the slot 16, guide plates 20 and 21 are attached to the under side of the top 15 to overlap the 70 slot 16 such that edges of the plates 20 and 21 project slidably into the grooves 22 and 23 provided therefor in the side faces of the crosshead 17. A spring 33, held by one end on the top 15, and pressing by the other end against the back end of the crosshead 17, 75 normally holds the crosshead in the forward end of the slot 16.

A U-shaped crank 24 straddles the crosshead 17 from below and is pivotally carried in a bearing 25 on each guide plate 20 and 21. The left end of the crank 24 extends through the left bearing 25 and upwardly and outwardly through a slot 26 in the top side 15 to form the external operating lever 80 27. The crank 24 pivotally carries a trigger 28 on its transverse member. This trigger 28 is formed such that it extends principally backwardly from the crank 24 along the under side of the crosshead 17 and is prevented from swinging downwardly about the 85 crank 24 by reason of a tail-piece 29 on the trigger 28 extending forwardly from the crank 24. This tail-piece 29 is of such length that it will project beyond the crosshead 17 when in its normal inoperative position as in Fig. 2, and further this projecting portion is bent to turn upwardly 90 slightly.

When the lever 27 is in the position as 100 shown by the full lines, in Fig. 2, such position being the normal inoperative position, the crank 24 presses the trigger 28 against the crosshead 17 throughout the length of the rear portion of the trigger 28, and springs 30, here shown as two in number, though one spring may be sufficient, are employed to hold the crank 24 in this position, by engaging one end of each spring to the 105 crank 24 and the other end to an ear 31 projecting from the top 15. As the lever 27 is pressed down forwardly to overcome the

resistance of the springs 30 to rock the crank 24 to the position as indicated by the dash lines, the rear end of the trigger 28 will tend to swing about the crank 24, to drop 5 downwardly due to its own weight, but being restrained by the tail-piece 29 will assume positions from between the full-lined position to the dash-lined position. (See Fig. 2.) As a further insurance that the 10 rear end of the trigger 28 will drop downwardly away from the crosshead 17, when the lever 27 is jerked rapidly, a spring 32 is fixed to the rear section of the trigger 28, as indicated in Fig. 3, to press against the 15 under side of the crosshead 17. Thus it is seen that the only movement resulting from operating the lever 27 is to carry the trigger 28 forwardly and backwardly without the trigger 28 engaging or moving other 20 parts.

A coin receiving slot 34 is cut through the top 15 back of the lever 27, Fig. 1, and a coin conveyor 35 is attached to the under side of the top 15 such that its inner passage-way 25 registers with the slot 34. A U-shaped guide 36, of such width that a coin 37 may roll freely on edge within, and open along the top side to permit a substantial portion of the coin to project therefrom, extends 30 downwardly from the conveyor 35 and transversely below the rear portion of the trigger 28, as in Figs. 2, 3, 4, and 5, to terminate with an open end on a line slightly back of the line with the right side face of 35 the crosshead 17. The crosshead 17 carries a coin stop 38, Figs. 2, and 4, of appreciable width, which stop 38 normally stands across the opening in the end of the coin guide 36, such that when the coin 37 is dropped in the 40 slot 34, the coin 37 is directed by the conveyor 35 to the guide 36 whereby the coin 37 rolls on edge downwardly to be stopped and retained in the guide 36 by contacting the stop 38, as indicated in Fig. 4.

Now should the lever 27 be rocked forwardly, the trigger 28 will be carried backwardly, but by reason of the coin 37 being below it, the trigger 28 can not swing downwardly by its rear end, but the rear end is 50 guided against and along the crosshead 17 by the trigger 28 sliding over the coin, such that the rear end of the trigger 28 is brought in contact against the ear 39 which projects downwardly from the rear end of the crosshead 17, and further travel of the lever 27 55 will cause the trigger 28 to so carry the crosshead 17 backwardly to overcome the resistance of the spring 33 such that the closure plate 18 is carried backwardly to uncover the ink well 19 as in Figs. 1, and 3. Since the stop 38 travels with the crosshead 17 and the coin guide 36 is stationary, the travel of the crosshead 17 as above described, 60 will carry the stop 38 beyond the guide 36 opening and the coin 37 will thereupon im-

mediately tend to roll out and drop to the bottom 10.

To insure the release of pressure of the trigger 28 upon the coin 37 when the stop 38 is removed from in front of the coin 37, to 70 permit the coin to drop, which pressure might be sufficient to retain the coin in the guide even though the stop is removed, the under side of the trigger 28 is tapered to 75 reduce its thickness from the original normal position point of contact on the coin 37 to near the crank 24, such that when the trigger 28 once engages against the crosshead ear 39 by reason of the trigger being directed there by the coin, the resistance of 80 the spring 33 against backward movement of the trigger 28 tends to hold the trigger in contact with the ear 39 without further guidance of the coin 37, and the clearance between the trigger and the coin effected as 85 above described may be provided without adversely affecting the action of the trigger.

Release of the lever 27 will permit the 90 springs 30 and 33 to return the crosshead 17 and trigger 28 to their normal positions.

As the mechanism has so far been described, the closure plate 18 will not uncover the ink well 19 through any rocking of the lever 27 unless a coin is inserted in the slot 95 34, but the closure plate 18 may be pushed backwardly, from without, independently of the lever 27, and to prevent such unwarranted action, a lock is provided as will now be described.

A slot is cut in each vertical face near the rear end of the crosshead 17 to serve as a retaining guide for each leg of the yoke 40 straddling the crosshead 17 from its under side. The yoke 40 has its transverse member adapted to contact normally the under face of the crosshead 17 immediately back of the ear 39, and the yoke 40 is slidingly retained on the crosshead 17 by a 100 spring 41 secured by one end to the crosshead and having its free end engaging one of the legs of the yoke 40, this spring 41 normally tending to hold the yoke 40 firmly up against the crosshead 17 so as to resist any downward travel. The two legs of the 105 yoke 40 project laterally from the slots and extend upwardly along the slots in the crosshead such that in the normal position their ends just clear the plates 20 and 21, as in 110 Fig. 2.

A lock plate 42 is fixed to each of the plates 20 and 21, to permit the passage of the crosshead 17 therebetween but having their forward edges located to be contacted by the legs of the yoke 40 upon the crosshead 17 tending to move forwardly. Thus, a 115 lock is provided and unless the yoke 40 is pulled downwardly to overcome the spring 41 and clear the ends of the yoke legs over the plates 42, the crosshead 17 and conse- 120

quently the closure plate 18 cannot be moved backwardly to uncover the ink well 19 either by moving the lever 27 or independently of the lever.

5 To release this lock when the coin 37 is inserted to effect legitimate operation of the mechanism, the rear end of the trigger is formed with an under face inclined acutely from the face of the crosshead 17 to effect 10 a chisel-like sharpened edge such that as this edge of the trigger 28 comes backwardly along on the face of the crosshead 17 as directed by the coin 37, this edge will slip under the cross member of the yoke 40, 15 thereby raising the yoke 40 with its legs until the edge of the trigger 28 is stopped by the ear 39 as before described, whereupon the crosshead 17 is then free to be carried 20 backwardly as the legs of the yoke 40 will now pass over the lock plates 42. The insertion of the trigger 28 under the yoke 40 is facilitated by bevelling or rounding the forward face of the cross member of the yoke 40, as shown in Fig. 3, where a section 25 of the yoke 40 is removed to disclose this formation.

Not only does the yoke 40 serve as a locking means as above described, but it also serves as a means for positively retaining 30 the trigger 28 against the ear 39 after the coin 37 has dropped from the guide. Release of the lever 27 will permit the springs 30 to withdraw the trigger 28 from under the yoke 40 to permit the yoke to spring 35 back into its normal locking position. It should be noted that the plates 42 are of such length that for any reason should the yoke 40 be prematurely released by the trigger 28, the crosshead 17 is free to travel 40 forwardly to its normal position, during which travel the ends of the legs of the yoke 40 may slide along over the plates 42 to their forward ends.

The manner in which the supply of ink 45 is had in the ink well 19 now remains to be described, and reference is now made to Fig. 6 as best showing the details. A boss 45 depends from the top 15 ahead of the slot 16 and has a central passage therethrough with 50 a bevelled countersunk upper end to act as a seat to support the ink well 19 thereon. A retaining ring 46 pressed in from above holds the ink well in position. Screw-threadedly engaging within the boss 45 from 55 the under side is the pump cylinder 47, and the ink well 19 depends from its upper flared end by a restricted cylindrical section within the cylinder 47, such that clearance is left between the ink well 19 and the cylinder 60 wall. The depth of the ink well 19 may be varied to hold that amount of ink desired to be dispensed for the coin.

The lower end of the cylinder 47 is open and contains a piston 48 carried on a cross-bar 49 which projects through the slots 50

in the cylinder wall to be connected with the piston rods 51.

An ink supply vessel 52 surrounds the cylinder 47 (Fig. 2) and is here shown as being supported thereon by means of the 70 catches 53 engaging within the ring 54 around the upper end of the vessel. Intake passages 55 are provided through the cylinder walls on a line just above the piston 48, when the piston is in the extreme lower 75 position, as here shown (Fig. 6), this position being the normal inoperative position. Within the cylinder 47, at a point beyond the required travel of the piston, is a closure 80 56 with a central passage 59 therethrough discharging into the reservoir chamber 57 above, into which chamber 57 the ink well 19 depends. A ball check 58 normally 85 closes the passage 59 against discharge backwardly from the chamber 57 to above the piston.

The operation is such that upon upper travel of the piston rods 51, the piston 48 closes the passages 55 and forces the ink having previously flowed therethrough from 90 the ink vessel 52, through the passage 59 to the chamber 57. Under usual working conditions, this chamber 57 is filled with ink to the level of the intake holes 60 provided in the ink well, these holes 60 being the 95 outlet for the discharge from the chamber 57, and the chamber 57 being filled to this level, further operation of the piston 48 will raise the ink in the chamber 57 such that it will flow through these holes 60 into the 100 ink well 19.

The travel of the piston 48 is normally regulated such that each upward stroke will place enough additional ink into the chamber 57 that will just fill the ink well 19 105 with sufficient ink for the filling of a single fountain pen, but it may happen that all of the ink was not used in a prior filling, in which event, the same fixed quantity of ink coming into the ink well 19 might cause 110 it to overflow. To avoid such a happening, and to prevent too much ink being offered for the single coin deposited, a number of holes 61 are provided through the ink well 19, above the holes 60 such that ink rising in 115 the ink well 19 to these holes 61 may discharge therethrough into passages 62 through the boss 45 outside of the cylinder 47, whereupon the excess ink so flowing may drop or pass down the outer wall of the 120 cylinder 47 back to the ink vessel 52. By this construction, the ink may never rise above the holes 61.

Each piston rod 51 is engaged by its upper end to a rocker arm 63 which is fulcrumed on the support 64 therebetween (Figs. 2 and 5), and each rocker arm is in turn engaged by a link 65. These links 65 pass one on each side of the crosshead 17 and are movably attached to the crosshead 130

17 by means of the screws 66 passing through slots 67 in the links 65. Springs 68 engage the rocker arms 63 at the pivotal connections with the links 65 and engage by 5 the other ends in the ears 69 such that these springs 68 normally tend to return and hold the rocker arms 63, and the engaged links 65 and piston rods 51 to the normal inoperative positions.

10 When the crosshead 17 travels backwardly the screws 66 come to the ends of the slots 67 and thus carry the links 65 backwardly so as to raise the piston 48 to effect the flow of ink into the ink well 19, and as the 15 springs 68 will carry the links 65 forwardly with forward travel of the crosshead 17, a continuous pumping action of the ink into the ink well 19 would be had by rocking the lever 27 forwardly and backwardly.

15 To prevent such pumping action after the initial raising of the piston 48, a catch 70 is extended from one link 65, here shown on the left hand link (Fig. 3) to engage on the post 71 when the backward travel of the 20 crosshead 17 has been carried to the point where the ink well 19 is just filled to the desired level, or, in short, at the end of the backward travel of the crosshead 17. Now as the crosshead 17 may be moved backward 25 and forward, there is no accompanying travel of the links 65 since the catch 70 holds the one link 65 against the spring 68 thereby preventing the return of the piston 48 to its lower position, and the screws 66 merely slide within the slots 67.

30 The catch 70 is released by being contacted by the arm 72 carried on the back end of the crosshead 17. This arm has a finger 73 extending forwardly that contacts the catch 70 on its inclined face and is so adjusted that the catch 70 is pressed away from engagement with the post 71 at the time the trigger 28 is released from the yoke 40, with the result that when the catch 70 is released 35 to permit pumping action, the trigger 28 is also released and no pumping can occur until the next travel of the crosshead 17 as regulated by the deposit of the coin.

Attention is now directed to the ink supply vessel 52. This vessel 52 is so formed 40 that it may be quickly and easily slipped up around the cylinder 47 to be engaged by the spring catches 53, and as quickly and readily removed when empty. In practice, 45 the ink is furnished in these vessels 52 such that it may be applied directly to the cylinder 47 and does not need to be poured from one vessel to another. The lower portion of the vessel 52 is formed with a sump 75 50 such that by the time the ink level in the vessel 52 drops to the line of holes 55, there is very little ink remaining in the vessel 52.

55 Numerous modifications may be had in the structure as shown without departing from the spirit of the invention, and we therefore

do not desire to be limited to this precise form.

What we claim as new and desire to secure by Letters Patent is:

1. In an ink vending device, a housing, a reciprocating crosshead, means for actuating the crosshead, an ink well carried by the housing, a plate cooperating with said crosshead normally closing said ink well, an ink supply vessel, and means operating in conjunction with said crosshead for transferring ink to said ink well from said ink vessel. 75

2. In an ink vending device, a housing, a reciprocating crosshead, means for actuating the crosshead, an ink well in the housing, an ink well closure plate cooperating with said crosshead, and means operating in conjunction with said crosshead for placing ink in 80 said ink well. 85

3. In an ink vending device, a housing, a reciprocating crosshead, means for actuating the crosshead, an ink well in the housing, an ink well closure plate cooperating with said crosshead, and an ink supply motor actuated 90 by said crosshead for supplying said ink well with ink. 95

4. In an ink vending device, a housing, a reciprocating crosshead, means for actuating the crosshead, an ink well in the housing, an ink well closure plate cooperating with said crosshead, and an ink supply motor actuated by said crosshead for supplying said ink well with ink, and means for arresting said motor following a predetermined ink discharge irrespective of further crosshead reciprocation. 100

5. In an ink vending device, a housing, a reciprocating crosshead, means for actuating the crosshead, an ink well in the housing, an ink well closure plate cooperating with said crosshead, and an ink supply motor actuated by said crosshead for supplying said ink well with ink, and means for arresting said motor following a predetermined ink discharge irrespective of further crosshead reciprocation, and return means to release said arresting means. 110 105

6. In an ink vending device, a housing, a reciprocating crosshead, crosshead actuating means, an ink well in the housing, an ink well closure plate cooperating with said crosshead, spring means normally retaining said crosshead at one end of its travel whereby said closure plate covers said ink well, an ink well supply motor, and a link extending from said crosshead to operate said motor. 115 120

7. In an ink vending device, a housing, a reciprocating crosshead, crosshead actuating means, an ink well in the housing, an ink well closure plate cooperating with said crosshead, spring means normally retaining said crosshead at one end of its travel whereby said closure plate covers said ink well, 125 130

an ink well supply motor, and a link extending from said crosshead to operate said motor, said link being adapted to operate said motor in one direction only, and spring means to operate the motor in the opposite direction.

8. In an ink vending device, a housing, a reciprocating crosshead, crosshead actuating means, an ink well in the housing, an ink well closure plate cooperating with said crosshead, spring means normally retaining said crosshead at one end of its travel whereby said closure plate covers said ink well, an ink well supply motor, and a link extending from said crosshead to operate said motor, said link being adapted to operate said motor in one direction only, and spring means to operate the motor in the opposite direction, and locking means cooperating between said link and said housing whereby said link is held in an inoperative position after a predetermined operation of the motor.

9. In an ink vending device, a housing, a reciprocating crosshead, crosshead actuating means, an ink well in the housing, an ink well closure plate cooperating with said crosshead, spring means normally retaining said crosshead at one end of its travel whereby said closure plate covers said ink well, an ink well supply motor, and a link extending from said crosshead to operate said motor, said link being adapted to operate said motor in one direction only, and spring means to operate the motor in the opposite direction, and locking means cooperating between said link and said housing whereby said link is held in an inoperative position after a predetermined operation of the motor, and a finger actuated by said crosshead to release said locking means upon the crosshead reaching a predetermined point.

10. In an ink vending device, a housing, a reciprocating crosshead, crosshead actuating means, an ink well in the housing, an ink well supply motor, a link extending from said crosshead to operate said motor, said link being adapted to operate said motor in one direction only, spring means to operate the motor in the reverse direction, and locking means to hold said motor in an inoperative position following a predetermined operation of the motor.

11. In an ink vending device, a housing, a reciprocating crosshead, crosshead actuating means, an ink well in the housing, an ink well supply motor, a link extending from said crosshead to operate said motor, said link being adapted to operate said motor in

one direction only, spring means to operate the motor in the reverse direction, and locking means to hold said motor in an inoperative position following a predetermined operation of the motor, and release means for disengaging said locking means, said release means being operative upon a predetermined crosshead travel.

12. In an ink vending device, a housing, an ink well in the housing, means for supplying ink to said ink well, a discharge conduit from said ink supplying means, said ink well intercepting said discharge conduit, and level control means whereby said ink well may not be filled above an indicated level, a cover normally closing said ink well, means for actuating said ink supplying means, said actuating means being adapted to open said cover and to limit the ink flow to a single filling of the ink well during such opened position of the cover.

13. In an ink vending device, a housing, a reciprocating crosshead, crosshead actuating means, an ink cylinder, a piston in the cylinder, an ink reservoir receiving the ink discharge from the cylinder, an ink well having an intake passage from said reservoir, means for preventing the overflow of said ink well, a link interconnecting by one end with said piston and having a longitudinal slot in the opposite end, a pin fixed to said crosshead and sliding in said slot, spring means for normally returning the piston to its intake position, a post on the housing, a catch on the link, whereby said catch engages said post after a travel of the link such that the piston travel has caused a predetermined displacement of ink from the reservoir, and a finger actuated by said crosshead to disengage said catch.

14. In an ink vending device, a housing, a reciprocating crosshead, crosshead actuating means, an ink well in the housing, means controlled by said crosshead for supplying ink to said ink well, and an ink supply vessel, said ink supply vessel being detachably engaged with said ink supplying means and having a sump therein.

15. In an ink vending device, an ink supply motor, an ink vessel adapted to receive a portion of said motor within, and yielding means to detachably secure said vessel about said motor.

In testimony whereof we affix our signatures.

OTIS AMOS.
CLAUDE A. DEAL.
